Paulson Wright

Patented Dec. 18, 1923.

UNITED STATES PATENT OFFICE.

HENRY PERCY LANCASTER, OF LONDON, ENGLAND.

PREPARATORY PILE USED IN THE CONSTRUCTION OF CONCRETE PILES.

Application filed January 29, 1923. Serial No. 615,606.

To all whom it may concern:

Be it known that I, HENRY PERCY LANCASTER, a subject of the King of Great Britain, residing at 104 Victoria Street, London, England, have invented certain new and useful Improvements in Preparatory Piles Used in the Construction of Concrete Piles (for which I have filed application in Great Britain Dec. 3rd, 1921), of which the

10 following is a specification.

This invention relates to preparatory piles such as are used in the construction of concrete piles, and has for its object to ensure that the concrete pile is not of less 15 diameter but preferably of greater diameter than that of the preparatory pile.

It has been found by long experience that in certain kinds of strata, for example peat and some kinds of clay, when the usual 20 preparatory pile is withdrawn to permit the filling with concrete, the surrounding strata will press into the opening and result in the pile being of less diameter than the original preparatory pile. The finished 25 pile is not only smaller than it should be in places but is irregular in form. Furthermore, where the concrete is tamped by the reciprocatory movement of the preparatory pile, a certain amount of the earth surrounding 30 the hole will fall into and mix with the outer portion of the concrete. My invention is particularly designed to prevent these objectionable results and to make it certain that the pile will be at least as 35 large as the preparatory pile and of concrete unmixed with any foreign substances.

According to this invention to the preparatory pile are secured two collars, one to its lower end, and mounted upon the pile is 40 a sleeve having a flange upon its internal upper end, which flange is capable of sliding between and is retained between the two collars on the pile, whilst the sleeve is large enough to pass over the lower of the collars. 45 The lower collar is preferably provided with an inwardly projecting flange which extends beneath the bottom edge of the pile tube.

If desired the collars may be made in one 50 piece with the pile tube.

The accompanying drawing shows sections of a pile made in accordance with this invention.

Figure 1 shows a pile driven into the 55 ground and a small quantity of concrete filled into the tube. Figure 2 shows a pile

in which the tube has been withdrawn a short distance from the shoe and also a rammer for tamping the concrete. Figure 3 shows a pile in which the sleeve has also 60 been raised from the shoe and in which the pile tube is used for tamping the concrete.

a is the tube of a preparatory pile having secured to it a collar *b* by rivets *c* and also a collar *d* by rivets *e*. On the collar *b* is a 65 flange *f* which extends beneath the end of the tube *a* whereby the life of the tube is lengthened and repairs can be easily effected. Free to slide upon the tube *a* between the collars *b* and *d* is a sleeve *g* having a flange *h* whereby the sleeve is retained upon the tube *a*.

In operation the tube *a* and sleeve *g* rest upon a shoe *j* and the pile is driven into the ground the required distance as shown 75 in Figure 1. Concrete is now filled into the tube *a* which is then withdrawn a short distance as shown in Figure 2. The concrete then escapes from the tube and is engaged by the sleeve and is tamped by a 80 rammer *k* thereby filling the sleeve with thoroughly compressed concrete which when the sleeve is withdrawn through the collar *b* engaging with the underside of the flange *h* forms a solid mass of concrete which will 85 not be affected by the pressure of the ground and a concrete pile will be formed of larger diameter than the tube *a* which will not be distorted as to shape or squeezed to a less diameter than the tube as is often the case 90 with piles as at present made.

Referring to Figure 3, it will be seen that the top of the collar *b* is below the bottom of the flange *h* of the sleeve *g*, as downward pressure has been applied to the tube *a* 95 whereby the concrete is tamped by the tube itself. The tube is usually given an up-and-down movement by which the sleeve *g* is slightly withdrawn on the upward stroke and the concrete tamped on the downward 100 stroke. The sleeve may be of any desired length, the position of the collars being adjusted according to its length.

What I claim is:—

1. A preparatory pile, a collar at the 105 lower end of the pile, a second collar on the pile spaced from the first collar, a sleeve of a diameter greater than that of the first collar and passing thereover, and a flange on the sleeve between the collars and of less 110 diameter than either collar whereby the pile may have a limited movement inde-

pendent of the sleeve thus ensuring the production of a permanent pile larger than the preparatory pile.

2. A preparatory pile, a collar at the lower end of the pile, a second collar on the pile spaced from the first collar, a sleeve of a diameter greater than that of the first collar and passing thereover, a flange on the sleeve between the collars and of less diameter than either collar whereby the pile may

have a limited movement independent of the sleeve thus ensuring the production of a permanent pile larger than the preparatory pile, and a flange on the lower collar extending inwardly beneath the end of the pile tube 15 to protect the same.

In testimony that I claim the foregoing as my invention I have signed my name this 18th day of January, 1923.

HENRY PERCY LANCASTER.
